UNITED STATES PATENT OFFICE.

JOSEPH C. CARY, OF NEW YORK, N. Y., ASSIGNOR TO JOHN H. J. RONNER,
OF SAME PLACE.

BOX FOR CARRYING BOTTLES.

SPECIFICATION forming part of Letters Patent No. 278,504, dated May 29, 1883.

Application filed March 8, 1883. (No model.)

To all whom it may concern:

Be it known that I, JOSEPH C. CARY, a citizen of the United States, residing at New York, in the county and State of New York, have invented new and useful Improvements 5 in Boxes for Carrying Bottles, of which the following is a specification.

This invention relates to a box for carrying bottles, which is constructed in a novel and 10 peculiar manner, as fully pointed out in the following specification, and illustrated in the accompanying drawings, in which—

Figure 1 represents a plan or top view, partly in section. Fig. 2 is a horizontal section in the 15 plane $x x$, Fig. 3. Fig. 3 is a transverse section in the plane $y y$, Fig. 1. Fig. 4 is an inverted plan. Fig. 5 is an end view, partly in section. Fig. 6 is a sectional view of one of the frames.

20 Similar letters indicate corresponding parts.

In the drawings, the letters A A designate the side pieces and B B the end pieces of my box. These pieces are all made of the same height, and the side pieces are secured to the 25 end pieces by means of nails. In the outer surfaces, near their ends, are formed grooves $a a$, which correspond in position with grooves $b b$, formed in the edges of the end pieces, and into these grooves are placed the strapping-wires 30 C, which are secured in position by means of staples c , and the ends of which are bent at right angles and driven into the wood, so that by the action of said strapping-wires the side pieces and end pieces are firmly held together.

35 I am aware that it is a common practice to strap boxes with hoop-iron; but such hoop-iron straps cannot conveniently be applied to my box, and, furthermore, my strapping-wires do not project above the surface of the wood, 40 so that they are protected against blows and are not liable to become loose; and I am also aware that barrels and boxes have been held together by strappings of wire laid into grooves and confined by staples and nails, and such

45 therefore I do not broadly claim. The bottom of my box is open, and it is formed of dowels D, which may either be fastened in the side pieces or in the end pieces, and which are round, so that they present no surface on which 50 the liquid can lodge, and that the box can be

easily kept clean. I am aware that open bottoms have been constructed of square slats; but such bottoms cannot be kept clean as easily as my bottoms, constructed of round dowels. In the example shown in the drawings the 55 dowels D are secured in longitudinal bottom strips, E, which are fitted into recesses d in the end pieces, B, and secured to the side pieces, A, by means of nails. Said bottom strips are provided with grooves e to receive the strapping-wires C, and by these means a very strong and durable box is obtained.

In the interior of the box are placed the frames F G, which are provided with cells to receive and sustain the bottles. The frame F, 65 which I use by preference, is constructed of a metallic rim, f , longitudinal strips f' , and transverse strips f'' , the strips f' and f'' being firmly secured at their ends to the rim f , while they are connected at their crossings by solder 70 or other suitable means. In the example shown in the drawings each of the longitudinal strips f' is provided with a series of incisions extending half-way up, Fig. 6, and the transverse strips f'' are provided with incisions 75 extending half-way down, to engage with the incisions in the longitudinal strips. The rim f is by preference made of metal wire, and it engages with grooves f^3 , formed in the inner surfaces of the side pieces, A A, and the end 80 pieces, B B. The frame G is constructed of longitudinal wires g and transverse wires g' , and they are connected at their crossings by cross-ties g^2 in addition to solder. The cross-ties are either made of wire or of sheet metal. 85 The ends of the wires g g' engage with grooves g^3 , formed in the inner surfaces of the side pieces, A A, and the end pieces, B B. After one of the side pieces, A, has been secured to the end pieces, the frames F G are slipped into 90 the grooves f^3 g^3 , and then the second side piece is secured in position.

What I claim as new, and desire to secure by Letters Patent, is—

1. The combination, substantially as hereinbefore described, of the side pieces, the end pieces, the recesses formed in the end pieces, the longitudinal bottom strips fitted into said recesses, and the transverse dowels secured in the bottom strips. 95

2. A box for shipping bottles, consisting of the side pieces and the end pieces having exterior grooves, and strapped together by wires confined in the grooves by staples, the longitudinal bottom strips arranged in recesses in the end pieces, the transverse dowels secured in the bottom strips, and cell-frames supported within grooves in the side pieces, substantially as described.
- 10 3. The combination of the side pieces and end pieces, grooved on their inner surfaces, with the frames composed of longitudinal and transverse wires having their ends arranged, respectively, in the grooves of the end and side pieces, and united at their crossings by cross-

ties and solder, substantially as and for the purpose described.

4. A frame for carrying bottles, composed of longitudinal wires and transverse wires, which are secured together by corner-ties and solder, substantially in the manner shown and described.

In testimony whereof I have hereunto set my hand and seal in the presence of two subscribing witnesses.

JOSEPH C. CARY. [L. S.]
